UNITED STATES PATENT OFFICE.

WILLIAM A. ARMOUR, OF THOMASTON, CONNECTICUT, ASSIGNOR TO SETH THOMAS CLOCK COMPANY, OF THOMASTON, CONNECTICUT, A CORPORATION OF CONNECTICUT.

ALARM-CLOCK-SETTING MEANS.

No. 936,454.

Specification of Letters Patent.

Patented June 29, 1909.

Application filed July 18, 1908. Serial No. 444,167.

To all whom it may concern:

Be it known that I, WILLIAM A. ARMOUR, a citizen of the United States, residing at Thomaston, Connecticut, have invented certain new and useful Improvements in Alarm-Clock-Setting Means, of which the following is a clear, full, and exact description.

My invention relates to a 24-hour setting mechanism for alarm clocks. Such an arrangement as I have shown is susceptible of a wide application, but is more particularly applicable to a continuous alarm such as disclosed in the drawings. I have also shown in connection with my invention an improved holding, releasing and restoring mechanism for the continuous alarm, for which a releasing mechanism is adapted to periodically release the alarm and allow it to ring until restored to normal position by hand, hand-operated restoring means which is adapted to shut off the alarm without locking it in its shut-off position but to shut it off and simultaneously place it in position to be again released by the next periodic action of the releasing mechanism. It therefore becomes desirable to have this periodic release of the alarm take place once in 24 hours, instead of 12 hours as heretofore, which necessitates the use of a setting means for setting the releasing mechanism to act at any predetermined time in the 24 hours. It is essential in all holding and releasing mechanisms for alarm clocks to have a relatively stationary portion for holding the alarm in operation and a movable portion operated by the clock movement to periodically coöperate with the stationary holding portion and release the alarm. In order to time the coöperative action between these portions, a setting means is usually provided and it is immaterial whether this setting means is mounted to have a fixed relation to the movable portion or fixed relation to the stationary portion, as the same results are obtained in either case.

In the preferred construction which I have shown in the present embodiment of my invention, I have attached the setting means to the movable portion which is operated by the clock movement.

My invention will be defined in the claims. In the drawings, Figure 1 is a front elevation of the clock movement and setting means; Fig. 2 is a similar view of a fragmentary portion of the same having the parts in

front of the line A—B Fig. 3 removed; and Fig. 3 is a section through the center of the setting means taken along X—Y Fig. 2.

The main frame of the clock movement is indicated at 1, and at the right side of said frame is shown the ordinary clock movement comprising a main spring 2 and pinions 3. The hour and minute hands operated thereby are indicated at 28 and 29, respectively. At the left end side of the frame 1 is shown a similar movement for operating a continuous alarm, that is, one which will ring from 30 to 40 minutes at a time, unless shut off. The main spring of said alarm movement is indicated at 4, the gear pinions at 5, and the bell at 6. The hammer 7 is operated by the usual pawl and ratchet construction 8 and 9 which need not be here specifically described. An arm 10 fixed in any suitable way to the pawl 8 extends over the top of a holding member 11 pivoted at 12, and when said holding member is held in its raised or normal position, the arm 10 of said pawl 8 prevents the same from being vibrated by the alarm movement, as is clear. A latch 13 pivoted on the main frame at 14 is provided with stops for retaining the holding member 11 in its raised or normal position through a pin 15 of said holding member and said latch 13, together with the holding member 11, constitute holding means to normally prevent the alarm from operating.

Means for restoring the holding member 11 to its normal position after the same has been unlatched to release the alarm, consist of a lever 16 pivoted at 17 on the frame, and having a cam notch 18 at its upper end for engaging a pin 19 of said holding lever. The lower end of lever 16 has a pin 17^a playing in the slot 18^a of a bell crank lever 19^a pivoted at 19^b for operating the same. A spring 20^a is provided for returning said levers 19^a and 16 to original position after being operated, to disengage the cam 18 from the pin 19 of holding lever 11.

In order to release the holding means a let-off device is provided which is operated by the clock movement and also adjustable with relation thereto in order to release the holding means any predetermined time in the 24 hours. The let-off device consists of a cam 20 carried on a sleeve 21 which is loosely mounted on an arbor 22 of the main frame. Surrounding the sleeve 21 and frictionally

engaging the same is the sleeve of the rotatable portion or dial member 23. This portion 23 has a pinion 24 fixed thereto adapted to mesh with a pinion 25 on the hour shaft to be constantly rotated thereby and is so geared as to rotate once with every two revolutions of the hour hand. To the outer end of said rotatable portion 23 and adjacent the clock face 24^a of the clock is fixed a dial 25^a. Said dial is divided off into two equal half portions or divisions, each division being regularly spaced by 12 numerals to indicate the hours of the day. One half division is indicated A. M. and the other, P. M. The let-off device is also provided with a pointer 26 fixed to its outer end which extends over the face of said dial to show the relative adjustment between said let-off device and said rotatable portion 23. Thus it is clear that the portion 23 with the dial 25 is constantly rotated by the clock movement, and that the let-off device 21, 20 is frictionally carried with said rotatable portion or dial member. Moreover, the let-off device may be adjusted by hand relative to said constantly movable portion 23 to properly time its action on the holding means, as may be desired. The cam 20 of the let-off device carries a pin 27, which, on the rotation of the cam, strikes against the lower end of the latch 13 and thereby unlatches the holding member 11, which thereafter rests by its outer end on the cam 20 as shown in dotted lines Fig. 2. With the further rotation of the cam the holding member 11 comes to the cut-away portion of said cam and drops into it to release the alarm mechanism.

The alarm may be stopped and all the parts returned to normal position ready for a new operation, by throwing the lever 19^a to the right as indicated in Fig. 2.

The operation of my setting mechanism is briefly as follows. Since the dial 25 is connected so as to be rotated by the hour hand but with only half the speed, it will be noted that all the points of this dial arrive in a position adjacent the end of the stationary holding member once in 24 hours, and for convenience we mark that part of the dial which happens to be opposite this position at 12 o'clock noon with the numeral 12. As the other numerals are regularly spaced around said dial, it is plain that the successive numbers 1 to 12 on the setting dial will arrive at a position opposite the end of the holding member each in an hour's difference of time. In other words, the numeral of the dial opposite the holding member will be the same as that indicated by the hour hand, to wit, the hour of the day. If, then, it is desired to set the alarm so that it will go off at any particular hour or time, the pointer 26, which is fixed on the let-off device 21 opposite the cut-away portion of the cam 20, is set opposite the proper numeral on the dial

25. This numeral of the dial indicated will reach its position opposite the end of the holding member at an hour of the day which corresponds to said numeral, at which time the pointer 26 and cam 20 will also be opposite said holding member to release the same and allow the alarm to operate.

What I claim is:

1. In combination, a clock movement, an alarm mechanism, holding means for normally preventing the operation of said alarm, a 24 hour dial member geared to the clock movement so as to be rotated thereby at all times at a speed of one revolution in 24 hours, a let-off device normally rotated by the clock movement only once in 24 hours but adjustable with relation thereto whereby said let-off device may be caused to operate at any predetermined time, a hand-operated indicator adjustable around said dial and connected to said let-off device to adjust the same.

2. In combination, a clock movement, an alarm mechanism, holding means for normally preventing said alarm mechanism from operating, a 24 hour dial member geared to the clock movement to be rotated thereby at all times at a speed of one revolution in 24 hours, a let-off device having a frictional sleeve connection causing it to move with said dial member and adapted to be normally operated thereby only once in 24 hours but being freely adjustable with relation thereto, a hand-operated indicator connected to said let-off device and arranged to move around said dial member whereby said let-off device may be adjusted to operate at any predetermined time.

3. In combination, a clock movement, an alarm mechanism, holding means for normally preventing said alarm from operating, a rotatably mounted let-off device, a 24 hour dial member having a frictional sleeve bearing surrounding the outside of said let-off device, said dial member being geared to the clock movement to be rotated thereby at all times at a speed of one revolution in 24 hours and normally carry with it said let-off device, a pointer connected to said let-off device and movable over the face of said dial member whereby said let-off device may be adjusted to operate at any predetermined time.

4. A clock having a 12 hour dial face, a movement, an alarm, a relatively stationary holding means, a let-off device rotated by the movement and adjustable with relation thereto, a two-part hand-operated setting means for setting said let-off device for operation at any predetermined time in the 24 hours, one of said parts being a pointer and the other a 24 hour setting dial, said pointer being connected to the let-off device to adjust the same to release the holding means at any predetermined time and adjustable with relation to the setting dial, said setting

dial being connected by gearing to the movement to be rotated thereby at all times at a speed of one revolution in 24 hours.

5. A clock having a 12 hour dial face, a movement, an alarm, a relatively stationary holding means, a let-off device rotated by the movement and adjustable with relation thereto and adapted to release said holding means and allow said alarm to operate until 10 said holding means is restored to normal position, a two-part hand-operated setting means for setting said let-off device for operation at any predetermined time within the 24 hours, one of said parts being a pointer 15 and the other a 24 hour setting dial, said pointer being connected to the let-off device to adjust the same to release the holding means at any predetermined time and adjustable with relation to the setting dial, said 20 setting dial being connected by gearing to the movement to be rotated thereby once in 24 hours and hand-operated means for restoring said holding means to normal position, thereby stopping said alarm.

25 6. In combination, a clock movement, an alarm mechanism, holding means comprising

a pivoted holding member for engaging said alarm, and a latch for retaining said holding member in normal position to prevent the operation of said alarm, a rotatable portion 30 geared to said clock movement to rotate once in 24 hours and having fixed thereto a 24 hour dial, a let-off device frictionally carried on said rotatable portion and adjustable thereon consisting of a pin for unlatching 35 said holding member and a cam for releasing the same and also having a pointer extending over the face of said dial to show the relative adjustment between said let-off device and said rotatable portion said let-off device 40 adapted to release said holding means at any predetermined time and allow said alarm mechanism to operate until said holding means is restored to normal position, and hand-operated means for restoring said holding means to normal position. 45

Signed at Thomaston, Conn. this 18th day of June 1908.
